UNITED STATES PATENT OFFICE.

WILLIAM J. VAN OSDEL, OF CHICAGO, ILLINOIS, ASSIGNOR OF ONE-HALF TO LOUIS SPERLING, OF CHICAGO, ILLINOIS.

SELF-WINDING CLOCK.

1,194,444.

Specification of Letters Patent. Patented Aug. 15, 1916.

Application filed September 20, 1915. Serial No. 51,511.

To all whom it may concern:

Be it known that I, WILLIAM J. VAN OSDEL, a citizen of the United States, residing at Chicago; in the county of Cook and State of Illinois, have invented certain new and useful Improvements in Self-Winding Clocks, of which the following is a specification.

This invention relates to improvements in self-winding clocks of the electric type, embodying gravity controlled means for actuating the same and electro-responsive means for shifting the gravity controlled means, and one of the objects of the invention is to simplify the construction of the same and to provide an improved base or support for the mechanism, which may be formed from a single piece or stamping, and improved means for securing the parts in position to strengthen and reinforce the parts.

A further object is to provide an improved form of actuating mechanism which may be constructed of stampings.

A further object is to provide improved means whereby the transporting or moving of the device when the parts are in certain predetermined positions, and in which position the armature or actuating means would not be influenced sufficiently to return the weighted actuating element to an operative position, will prevent closing the circuit through the electro-responsive devices and holding the armature in a position to prevent the movement of the weighted actuating means.

To the attainment of these ends and the accomplishment of other new and useful objects as will appear, the invention consists in the features of novelty, in substantially the construction, combination and arrangement of the several parts, hereinafter more fully described and claimed and shown in the accompanying drawing, illustrating the invention, and in which—

Figure 1 is a front elevation of an improved device of this character constructed in accordance with the principles of this invention. Fig. 2 is a sectional view as taken on line 2—2, Fig. 1. Fig. 3 is a bottom end elevation. Fig. 4 is a detail sectional view taken on line 3—3, Fig. 1. Fig. 5 is a front elevation of the armature. Fig. 6 is a front elevation of the gravity actuating element. Referring more particularly to the draw-

ing, the numeral 10 designates a supporting base, which may be of any desired size and configuration and constructed of any suitable sheet material, which is stamped into shape and is provided with an opening 11 formed by stamping a portion 12 therefrom and deflecting the portion 12 laterally with respect to the base. This portion 12 may be of any desired size and configuration and serves as a means for supporting one extremity of the electro-responsive devices or coils 13. The electro-responsive devices are secured to the portion 12 by means of suitable fastening devices 14, and one end 15 of one of the electro-responsive devices 13 projects into the opening 11, and abuts the edge 16 of the base 10 adjacent the opening 11, so that when the electro-responsive devices are secured to the portion 12, the latter will be reinforced or strengthened owing to the fact that the end of the electro-responsive device engages the wall of the opening 11 and this will impart strength and rigidity to the portion 12, thereby rendering it possible to construct the base from comparatively light material. The base is also provided with another opening (not shown) adjacent the clock movement 17, for the purposes of lightness. The clock movement is provided with a shaft 18 connected with which is a ratchet wheel 19 and pivotally mounted upon the shaft 18 is a gravity actuating element 20 which moves freely about the shaft and is held in position preferably by means of a collar or shoulder 21 adjacent the ratchet 19 and a collar 22 which is held in position in any suitable manner such as by means of a cotter pin 23 passing through the shaft. The member 20 is provided with an extension 24 and pivotally connected therewith is a dog 25 which engages the teeth of the ratchet 19 and a spring 26 controls the dog. The element 20 is also provided with a laterally projecting pin 27 for a purpose to be hereinafter described, and also a laterally projecting pin 28, which is spaced from the pin 27, also for a purpose to be hereinafter described.

An armature 29 is pivotally supported by means of a bracket 30 secured to the base 10 in a position to coöperate with the electro-responsive device 13, and the armature 29 is provided with an upwardly extending deflected portion 31 which has secured to it

2

a contact 32 insulated therefrom as at 33, and the end 34 of the contact extends over the end of the armature 31 and is bent as at 35 to stand adjacent the opposite face of the armature 31 and also adjacent a contact 36 carried by the armature. The portion 35 of the contact 32 stands and moves between the contact 36 and also the lateral projection 27 which forms a second contact 10 which coöperates with the contact 32. The armature 31 is provided with a projecting pin or shoulder 37 which coöperates with the pin or projection 28 on the element 20 in a manner to be set forth. A weighted element 38 also constructed preferably of a stamping is pivotally supported as at 39 and is provided with a portion 40 which extends into the path of movement of the projection 27 of the element 20, when the latter is returned to an operative position. A retaining dog 41 also preferably constructed of a piece of stamped material is pivotally supported as at 42 and coöperates with the ratchet 19 to prevent retrograde movement of the latter. A pin or projection 43 is supported by the clock movement casing and is arranged with respect to the retaining dog 41 so as to prevent the latter from being accidentally disengaged or 25 swung to such a position that it will not coöperate with the ratchet 19.

In operation, the clock movement is given motion by means of the gravity actuating element 20, which tends normally to move in a direction to rotate the ratchet 19. When the element 20 is moved into such a position as to cause the projection or contact 27 thereon to engage the portion 35 of the contact 32, the circuit will be completed through the electro-responsive devices 13 thereby energizing them which will attract the armature 29 and the portion 31 of the armature will be moved in a direction to cause the portion 35 to operate upon the projection or contact 27 and thereby move the element 20 about its pivot into an operative position. The momentum of the armature will cause the weighted element 20 to travel some distance after the armature stops moving. 30 When the contact 27 moves into engagement with the portion 35 of the contact 32 the circuit will be completed and the armature will be attracted, causing the contacts 35, 36 to move into engagement and the element 20 to be shifted by the armature, the momentum imparted thereto will cause the contact 27 and the portion 35 of the contact 32, which latter is of an elastic nature, to move out of engagement with the contact 36, while it is still in engagement with the contact 27, thereby preventing sparking between the contacts 35 and 36 to overcome corroding of the latter, and the portions 34, 35 of the contact 32 are so constructed as 35 to cause a sliding movement between the contacts 35, 36 to keep the latter polished. As soon as the electro-responsive devices are de-energized, a spring 44 will return the armature 29 to normal position and the weighted element 20 will then move in a direction to 70 rotate the ratchet wheel 19. Just before the weighted element 20 reaches the limit of its movement under the influence of the armature, the projection or contact 27 will engage the portion 40 of the weighted element 38, 75 to arrest the movement of the element 20, and the weighted element 38 will then operate upon the element 20 to assist in starting it in its direction of operating movement.

Unless some provision is made to prevent the closing of the circuit through the electro-responsive devices, before the armature 29 could actuate the element 20, the armature might be moved into a position that it would contact with the shaft 18 or the portion 35 of the contact 32 would engage the contact 27. Such a condition would only occur when the element 20 is in a position that the contact 27 has assumed a position with respect to the shaft 18, that the armature if moved over would engage the shaft and contact 27, and the contact 27 would not be sufficiently advanced that the armature would act thereon to throw the element 20 backwardly about its pivot. This 80 would close the circuit through the batteries and would exhaust the batteries if this condition is not discovered. In order therefore to obviate this objection, the projection 28 is provided on the element 20 and 85 the projection 37 is provided on the portion 31 of the armature 39. These projections 28, 37 are of such a size that if the device is transported or moved under predetermined conditions, and which are the only 90 conditions that would close the circuit in the manner just set forth, they will engage each other and prevent the armature from moving into a position to close the circuit through the electro-responsive devices. 95

In order to obtain the results desired, it is necessary that the armature 29 when attracted by the electro-responsive devices, shall cause the portion 31 to move a certain distance only and inasmuch as the portion 31 is bent or deflected with respect to the portion 29, the parts cannot always be properly positioned with respect to each other during the course of manufacture and it therefore becomes necessary to bend the 100 portion 31 with respect to the portion 29. In order to facilitate this bending there is provided a weakened portion 45 between the portion 29, 31 which renders it easy to bend or deflect the portion 31 with respect to the portion 29. The trunnions 46 are formed on the armature 29 by turning down a portion of the armature. 105

With this improved construction it will be manifest that a very cheap support or 110

base is provided for the structure and that the electro-responsive devices or coils 13 will reinforce the portion 12 which is stamped from the base and to which the electro-responsive devices are secured, so that a comparatively light base may be used and all of the operating parts being constructed of stampings, the cost of manufacture will be materially decreased.

10. What is claimed as new is:

1. A device of the character described, embodying clock mechanism, actuating means therefor, electro-responsive means for controlling the said actuating means, and a supporting base for said parts, said base being constructed of a single piece of sheet material having a portion thereof cut and deflected to form a projection to which the electro-responsive means is secured, a portion of the electro-responsive means projecting into the opening formed by the cut-out portion and abutting the edge of said opening to brace the said deflected portion.

2. A supporting base for electric self-winding clocks, said base constructed of a single piece of sheet material formed into shape and having a portion cutout and deflected to form a lateral projection and an opening in the base adjacent the projection, an electro-responsive coil disposed to project into the opening with one end secured to the projection and the opposite end abutting the edge of the opening opposite the projection to brace the latter.

3. A self-winding clock embodying an operating shaft, gravity actuated means for actuating the shaft, electrically actuated means for returning the gravity actuated means, said electrically actuated means embodying spaced contacts movable into and out of engagement with each other, and means for arresting the movement of the contacts one with relation to the other to maintain the contacts spaced.

4. A self-winding clock embodying an operating shaft, gravity actuated means for actuating the shaft, electrically actuated means for returning the gravity actuated means, said electrically actuated means embodying spaced contacts movable into and out of engagement with each other, and stop mechanism for maintaining the contacts spaced.

5. A self-winding clock embodying an operating shaft, gravity actuated means for actuating the shaft, electrically actuated means for returning the gravity actuated means, said electrically actuated means embodying spaced contacts movable into and out of engagement with each other, and cooperating means operatively related to the

contacts for holding the contacts in inoperative relation.

6. A self-winding clock embodying an operating shaft, gravity actuated means for actuating the shaft, electrically actuated means for returning the gravity actuated means, said electrically actuated means embodying spaced contacts movable into and out of engagement with each other, and means operatively related to the contacts for rendering the said electrically actuated means inactive.

7. A self-winding clock embodying an operating shaft, gravity actuated means for actuating the shaft, electrically actuated means for returning the gravity actuated means, said electrically actuated means embodying spaced contacts movable into and out of engagement with each other, and means controlled by the said gravity actuated means for maintaining the said electrically actuated means inactive.

8. A self-winding clock embodying an operating shaft, gravity actuated means for actuating the shaft, electrically actuated means for returning the gravity actuated means, said electrically actuated means embodying an armature and spaced contacts, said contacts movable into and out of engagement, and means connected with the said gravity actuated means and adapted to be positioned in the path of movement of said armature to arrest the movement of the armature and maintain the contacts spaced.

9. A self-winding clock embodying an operating shaft, gravity actuated means for actuating the shaft and embodying an element loosely mounted upon the shaft, electrically actuated means for returning the gravity actuated means and embodying an armature, spaced contacts, one of said contacts connected to and movable with the armature, said contacts movable into and out of engagement, and a projection carried by the said element and adapted to be positioned during a portion of the movement of said element, into the path of the movement of the armature in a direction to cause the contacts to engage, for arresting such movement of the armature to maintain the contacts in an inoperative relation.

In testimony whereof I have signed my name to this specification, in the presence of two subscribing witnesses, on this 13th day of September, A. D. 1915.

WILLIAM J. VAN OSDEL.
